UNITED STATES PATENT OFFICE.

JOHN LUCAS, OF PITTSBURGH, PENNSYLVANIA, ASSIGNOR TO LEWIS FOUNDRY & MACHINE COMPANY, OF PITTSBURGH, PENNSYLVANIA, A CORPORATION OF PENNSYLVANIA.

AX AND PICK MACHINE.

Application filed March 26, 1926, Serial No. 97,539. Renewed August 27, 1928.

This invention relates to a machine for manufacturing ax heads and pick heads.

One object of the invention is to provide a machine in which the die holding means 5 may be readily changed to adapt the machine to the manufacture of either ax heads or pick heads.

Another object of the invention is to provide a punching or forging machine in which 10 two cross heads may be actuated simultaneously, or which may be readily adapted for the actuation of one cross head alone.

Another object of the invention is to provide a die for use in the punching of pick 15 heads and ax heads which holds the blank on four sides during the punching operation.

As the dies for punching pick heads or ax heads and the dies for forming ax heads are not interchangeable in their holders, the 20 present machine secures its double function by means of a construction which renders the die holders themselves interchangeable.

In the accompanying drawings Figure 1 is an end elevation of the ax and pick machine; Figure 2 is a side elevation of the holder for the upper dies for forming ax heads; Figure 3 is a cross sectional view through such die holder on line 3—3 Figure 2; Figure 4 is a side elevation of the machine, showing ax punching dies in operative position, and showing the holders for ax forming dies; Figure 5 is a side elevation of the holder for the lower ax forming die; Figure 6 is an end elevation of such die holder; Figure 7 is a plan view of such die holder; Figure 8 is a partial side elevation of the machine, showing both of its elements equipped with punching dies adapting it to the manufacture of picks; Figure 9 is a side 30 elevation of the member in which the stock holding dies are mounted; Figure 10 is a plan view of such die holder; Figure 11 is a fragmentary sectional view showing the mounting of the member shown in Figure 9 and Figure 10, with side stock holding dies positioned therein, and showing a punching die holder with the die mounted therein; Figure 12 is a plan view of the upper punching die holder; Figure 13 is a side elevation of such die holder; and Figure 14 is a sectional view on the line 14—14, Fig. 4, showing the arrangement of the end dies for holding ax stock for punching.

The frame work of the machine comprises

a base 1, a central housing 2, and side housings 3 and 4. Mounted in the base 1 are die supporting tables 5 and 6; the die supporting table 5 being disposed between housings 2 and 3, and the die supporting table 6 between the housings 2 and 4. Adjacent the upper extremity of the machine is a main shaft 7, which is divided part way of its length but the divisions of which may be interconnected by suitable bolts passing through collars 8. At one end of shaft 7 is loosely mounted a gear 9, which meshes with a pinion 10 on a driving shaft 11. Driving shaft 11 has thereon a pinion 12 meshing with a pinion 13 on the shaft of an electric motor 14. On shaft 11 are mounted two fly-wheels 14^a and 14^b to relieve the motor as the dies punch or form the stock.

A clutch 15 serves to connect gear 9 operatively with the main shaft 7 at the will of the operator of the machine. Clutch 15 is operated by means of a bell crank lever 16 connected at the extremity of one of its arms to the clutch 15, and which is pivoted on a shaft 17 in bracket 18 affixed to base 1. A coiled spring 19 exerts a downward force on the horizontal arm of bell crank 16, tending to maintain the clutch in its engaged position to fixedly connect the gear 9 with the main shaft 7.

Slidable in guides 20 and 21 are cross heads 22 and 23, which are acted upon respectively by eccentrics 24 and 25 on the main shaft 7. Brake blocks 26 and 27 are mounted to contact the shaft 7 and operate to retard the motion at all times, so that when the clutch is disengaged on the upward stroke of the cross heads the motion is soon stopped. Extending from the cross head 22 is an arm 28 which is also loosely mounted on the shaft 17. A locking pin 29 is mounted in bell crank arm at 16^a and is normally forced by a coiled spring 30 into a position to engage the top surface of arm 28 which oscillates with movement of cross head 22.

With locking pin 29 in this position, arm 28 when rising acts to lift the lower arm 16^a of the bell crank and thus throw arm 16^b of the bell crank outwardly and disengages the clutch 15 as the cross head 22 approaches the upper limit of its movement.

Adjacent the outer extremity of locking pin 29 is a projection 31, which lies in an

eye 32 on a small bell crank lever 33, which is pivoted at 34 on the bracket 18. To the other arm of bell crank 33 is a rod 35 connected with a treadle 35^a.

5 When treadle 35^a is depressed, bell crank 33 is oscillated to withdraw locking pin 29 from its position interengaging the arm 28 and bell crank 16. This permits the clutch to become engaged by the force exerted by 10 coiled spring 19, and produces actuation of the cross heads so long as the treadle is maintained in its depressed position.

The upper punching die holder 37 for the 15 punching of axes and picks is shown in detail in Figures 12 and 13. This die holder comprises a body portion 38 and side guide portions 39. Extending from the body portion of the die holder is a member 40 for the attachment of arm 28, the function of 20 which has been previously described. The guide portions 39 engage in tracks in the housings 2 and 3, and are held in place by guide strips 42 which are removably secured to the housings by bolts 43. The lower face 25 44 of the cross head has therein a socket 45 for the reception of a punching die.

The side die carriers 46 are pivotally mounted in the lower die holder 47 supported by the table 5. The upper, or head, 30 portions 46^a of the die carriers hold the side dies 48. Tail members 46^b extend downwardly from the head portions of the dies, and have bearing against them coiled springs 49 on a rod 50 which extends between the 35 housings 2 and 3 and 2 and 4. These side die carriers are actuated by a sliding contact with the upper die holder 37. For this purpose the lower face 44 of the upper die holder has thereon beveled surfaces 51 arranged to contact beveled surfaces 52 on the head portion of the die holders. Downward movement of the upper die holder thus forces the head portions of both die carriers inwardly, while the force exerted by coiled 40 springs 49 on the tail portions of the die carriers tends to separate the dies upon upward movement of the upper die holder.

As shown in Figure 8, this portion of the machine is equipped for the punching of 50 pick heads. As shown in Figures 4 and 14, however, it is equipped for the punching and forming of ax heads. As shown in these latter figures of the drawings, end dies 53 and 54 are also provided. Of these the die 53 is mounted in a bracket 55 secured to the base 1 of the machine, and is adjustable horizontally by means of an adjusting bolt 56. The die 54 is carried by a die holder or 55 chuck 57. Die holder 57 has thereon a flange 60 58 which is provided with a beveled surface 59 arranged to be contacted by a beveled extension 60 on a vertically movable arm 61. Downward movement of the arm 61, which is actuated by movement of the cross head 65 22 and die holder 37, serves to force the die

54 inwardly to perform a forming operation on the stock from which the ax head is made. This operation take place simultaneously with the punching operation. Rearward movement of the die holder is produced by 70 means of a flat spring 62, which engages the die holder 57 and is secured to the base 1 of the machine. This spring is placed under tension by inward movement of the die holder, and exerts a force which causes outward movement of the die holder after the 75 arm has moved upwardly therebeyond.

In order to adapt this side of the machine to the punching of pick heads, the bolts 43 are disengaged and the guide strips 42 are 80 removed. The upper die holder 37, carrying with it the vertical arm 61, can then be readily removed, permitting the removal of die 54 and die holder 57. The side dies in members 46 are changed as needed to hold 85 the pick stock. Bracket 55, in which die 53 is mounted, and which may be secured to the base of the machine by bolts 59, is also removed; and this leaves the machine in condition for the insertion of a substituted 90 upper die holder. This die holder for the punching of pick heads may be identical with that for the punching of ax heads. Front and rear dies are, however, unnecessary for performing the pick punching operation, so they are omitted from the assembly.

In Figure 8 the side of the machine is shown equipped with pick punching dies generally similar to those described immediately above. The reason for two punching dies is because the helve hole in a pick head is punched by two operations, and the dies for performing these operations differ slightly from each other in size and shape. 105

In Figure 4 the machine is shown provided with ax punching dies and with holders for the forming dies for ax heads. This is for the reason that the helve hole for ax heads may be punched by a single set of dies; 110 and the head formed by a second set. In Figure 4 the upper die holder 63 is shown as bolted to the cross head 23, and the lower die holder 64 as centered on the table 5 by means of pins 65. These die holders are of 115 the simple structure which is desirable for holding forming dies.

The cross head 23 and upper die holder 63 are slidably engaged in tracks 21, and are held in position by means of guide strips 42 120 secured by bolts 43. These guide strips also may be readily removed for a change of die holders.

The changes which adapt the machine to its several purposes are simple and may be 125 expeditiously made. It is economical because the punching of the pick heads, and the punching and forming of the ax heads are operations which may be quickly performed, and the continuous use of a ma- 130

chine for an extended length of time is unnecessary in a plant of average size.

If the right hand side of the machine is to be used alone for either the punching or forming of ax heads, the left hand side may be disconnected. This is effected by disconnecting the two sections of shaft 7, and by mounting the gear 69 and pinion 70 on extensions 71 and 72 of main shaft 7 and driving shaft 11 respectively. The left hand side may also be used alone to perform a punching operation on either ax heads or pick heads.

What I claim is:

1. In a machine for punching pick and ax heads the combination of a machine frame, vertical tracks in said frame, a cross head slidable in said frame, an upper punching die holder slidable in said frame, a lower punching die, a pair of opposed holding dies

pivotaly mounted in said lower punching die, said pivoted holding dies and the upper die holder having co-operating surfaces arranged to force the holding dies toward each other during downward movement of the cross head, a holding die slidably mounted at right angles to said pivotally mounted dies, and means carried by the upper die holder for actuating said slidale die.

2. A die structure comprising the combination of a punching die, a pair of opposed holding dies pivotally mounted in said punching die, a stationary holding die, and a holding die slidale toward and from said stationary die, the slidale die being mounted for motion at approximately right angles to said pivotally mounted dies.

In witness whereof, I hereunto set my hand.

JOHN LUCAS.
